UNITED STATES PATENT OFFICE.

FRANK REES, OF NEW YORK, N. Y.

REPEATING FIRE-ARM.

SPECIFICATION forming part of Letters Patent No. 337,993, dated March 16, 1886.

Application filed December 18, 1885. Serial No. 186,049. (No model.)

To all whom it may concern:

Be it known that I, FRANK REES, of the city and State of New York, have invented an Improvement in Repeating Fire-Arms, of which the following is a specification.

The present invention relates to improvements upon and modifications of the devices set forth in my application, No. 162,546, filed April 17, 1885, and a reference is hereby made to the said application for a general description and mode of operation of the respective parts, and I remark that the same letters of reference made use of herein refer to corresponding parts in the aforesaid application.

In my present improvement I make use of a peculiar stop mechanism for preventing the carrier revolving when the supply of cartridges has been exhausted, and I combine with the said stop and carrier a clamping-screw to hold the end of the follower in its proper position, and make the gun a single-firing arm, so that the carrier may be revolved and the cartridges supplied one at a time by hand, and I construct the sear and its latch and sear-spring with reference to allowing the sear to be held and the firing-pin retained by the sear when the trigger is pulled, and the tumbler and carrier revolved for withdrawing the cartridge and ejecting the same without firing it, and I combine with the trigger and its hook a blocking-piece that acts against the cog-teeth on the tumbler to prevent the arm being fired should the tumbler have failed to complete its movement by the spring becoming exhausted, and I combine with the door of the ejecting-chamber a peculiar axle, crank-arm, and spring for closing said door, and a catch for holding the door open when inserting cartridges separately by hand.

In the drawings, Figure 1 is an elevation with the lock-plate removed. Fig. 2 is a cross-section near the line $x-x$ at the rear of the barrel and the follower of the magazine, and the parts connected therewith. Fig. 3 is a section near the line $y-y$ of Fig. 2, showing the rear end of the barrel and part of the magazine-tube in section. Fig. 4 is a detached view, partly in section, of the finger-piece and its head for moving the follower in the magazine. Fig. 5 is an elevation of part of the rear end of the barrel, the magazine and its follower,

and a clamping-screw. Fig. 6 shows the frame at the stock or butt portion of the gun, with the spring-tube in section. Fig. 7 is an elevation of the stationary lock-frame and parts connected with it. Fig. 8 is a cross-section at the line $z-z$, Fig. 7. Fig. 9 is a partial cross-section at the line $y'-y'$, Fig. 7. Fig. 10 is a detached view of the revolving tumbler, trigger, and parts connected therewith. Fig. 11 is a cross-section of the housing and of one of the toggles, and a rear elevation of the revolving tumbler and the blocking-piece upon the trigger. Fig. 12 is an elevation, and Fig. 13 is a section, of the extension-magazine below the barrel. Fig. 14 shows a portion of the chain, and Fig. 15 is a partial plan showing the locking-shaft and a part of the firing-sear.

The chain H^2 passes from the chain-wheel near the butt of the stock beneath the pulley H^1 and to the chain-wheel I , that gives motion to the tumbler as in my aforesaid application; but I construct the chain of long and short links, the long links being in pairs, and the short links occupying intermediate positions, as shown in Fig. 6, and in the detached view, Fig. 14, the object of this construction being to obtain the spaces necessary for the teeth of the chain-wheels, so that said teeth may project up between the links 11 and come against the ends of the links 22. In this manner the teeth are made sufficiently large to obtain the necessary strength, and the links of the chain are straight and not liable either to slip upon the chain-wheels or to break in consequence of the sudden stopping and starting of the parts.

In Fig. 6 I have shown a helical spring, H^6 , within the tube H^7 , and having a follower, H^8 , and a chain, H^9 , to the fusee-barrel H^10 upon the winding-shaft h^1 . This chain H^9 preferably passes around a pulley, H^11 , so as to obtain the desired length for the tube H^7 containing the expansive helical spring H^6 . The end of the chain is attached to the barrel H , where the fusee is of the largest diameter, hence the power of the spring is nearly equalized, because as the spring is compressed and becomes more powerful the chain is wound upon a smaller part of the barrel.

The tumbler K and the parts connected with the same that revolve the carrier and

give motion to the breech-bolt and the toggle-links at the rear end of the breech-bolt are the same as in the aforesaid application; but in cases where the spring is nearly exhausted 5 the stud i' upon the cam i may not have sufficient power to press the toggle-links $L^3 L^4$ upwardly against the action of the spring t , and if the arm should be discharged while in 10 this position the breech-bolt might be blown back. I therefore provide upon the hooked end f^3 of the trigger F' a blocking-piece, f^6 , projecting as an arm that comes at its end close against the cogs 7 upon the rear of the tumbler K ; but when the tumbler K receives 15 its entire movement and the toggle-links $L^3 L^4$ are properly placed and held by the stud i' , the end of the blocking-piece f^6 swings with the trigger and passes in under and below the lower tooth, 7 , upon the tumbler K in the act 20 of discharging the piece, but the trigger cannot be moved when the tooth 7 is in line with the end of the blocking-piece f^6 . The end of this blocking-piece f^6 may be slightly inclined so as to press beneath the tooth 7 upon the 25 tumbler K , and partially raise the same in cases where the parts are very near to the correct position.

The action of the trigger F' , trigger-sear S , trigger-latch S' , sear n^2 for the firing-pin, and 30 the parts connected with the same correspond to those set forth in the aforesaid application except that the jointed end n^6 of the sear arm n^3 is made in the manner next described.

The spring n^5 acts against an incline upon 35 the sear end n^6 , and at the joint 27 there is a shoulder upon the sear end n^6 , and a latch, n^8 ; upon the sear-arm n^3 , which, taking against the shoulder upon the sear end n^6 , causes the sear-arm and sear to be moved by the trigger-sear S in firing the gun. If, now, the shaft t^2 is turned in one direction by the finger-piece t^3 , the safety-lock t is brought against the sear end n^6 , as in the aforesaid application, and 40 locks the parts so that the trigger cannot be moved and the gun cannot be fired; but if the finger-piece t^3 and shaft t^2 are moved in the other direction the arm t^4 comes against the latch n^8 , unlatching the end from the shoulder of the sear n^6 , and at the same time 45 forming a blocking-piece that holds the sear-arm n^3 above the hinge-joint 27 firmly. If, now, the trigger is pulled, the end of its sear S swings the sear end n^6 upon its hinge 50 27. At the same time the revolving tumbler K is liberated, and all the parts are free to be moved except the firing-pin; hence under 55 these circumstances a cartridge can be withdrawn from the barrel and the carrier revolved, and the cartridge ejected without being exploded.

In my aforesaid application a lock-frame, I^2 , is recessed to form the filling and ejecting chamber M , and the spring-door m swings upon the hinge-pin 12, and there is a helical 60 spring for closing the door. I find it preferable to connect the hinge-pin and the door together by a square upon the hinge-pin en-

tering a similar opening in one knuckle of the door-hinge, and at the end of said hinge-pin 12 I make use of a crank-arm, 30, (see Figs. 7 and 8,) against which crank the flat spring 31 bears and turns the pin 12 to close the door m , and this door m is opened by the ejector P , that is hung from the hinge-pin 12 and provided with a shoulder against the inner face 75 of the door m , and the finger 14 upon the axis r' acts against the ejector P to move the same for throwing out the cartridge case or shell, and at the same time the door m is opened by the shoulder upon the ejector. The axis r' is 80 provided with the arm r , against which the cam i^2 acts, as in my aforesaid application.

When the cartridges are being supplied by hand into the chamber M , it is convenient to hold the door m open. I accomplish this by 85 means of a spring-catch, m^6 , upon the side plate, E . (See Fig. 9.) This spring-catch m^6 passes into a mortise in the finger-piece m^2 of the door m and the spring-catch yields to allow the door to close when sufficient pressure 90 is applied to the door. The follower c' is within the magazine-tube C , and against it the spring c acts to move the cartridge along into the revolving carrier. Upon this follower c' is a ring-flange, 1, and the stop-piece 95 c^2 and finger-piece c^3 are provided as in said application to prevent the follower c' passing out into the revolving carrier. When the last cartridge has been conveyed away by the carrier from the magazine, the end of the follower c' projecting into the carrier prevents the same being revolved. I combine along with this stop c^2 and the finger-piece c^3 a gravity-latch, c^6 , occupying a slot in the stem of the stop c^2 . (See Figs. 3 and 4.) This gravity-latch drops into the position shown in 100 Fig. 3 and prevents the finger-piece c^3 being moved forward when the fire-arm is held in a horizontal position, because the end of the gravity-latch drops over and catches against 105 a portion of the housing. If, now, the fire-arm is held in a vertical position, this gravity-latch will hang out of the way of the housing, and the finger piece c^3 and stop c^2 can be moved so as to draw the follower c' out of and away from the end of the revolving carrier G . The object of this construction is to insure the dropping out of the spent-cartridge case, because, if the arm occupied a horizontal position when the follower c' is moved forward the carrier 110 115 G would revolve and the spent-cartridge shell would remain in the carrier and be carried again into the barrel; but the gravity-latch c^6 compelling the person using the arm to hold the same in a vertical position before the follower can be moved insures the discharge of the spent-cartridge shell, because it drops by gravity back into the ejecting-chamber M .

In Figs. 2 and 5 I have shown the holding-screw c^1 as passing in through the metal of 120 the housing with its point adjacent to the follower c' . The object of this is to allow the arm to be used conveniently as a single-firing gun when cartridges are supplied one at a time.

through the filling and ejecting chamber M instead of being introduced into the magazine. With this object in view, the screw c' is screwed in and its end comes between the two collars upon the follower c' . This allows the follower to spring into the forward end of the revolving carrier, and prevent such carrier being revolved until such follower is pressed back by the end of a cartridge supplied by hand through the chamber M into the carrier, and the follower holds the carrier until the spent shell is ejected. The screw c' can be screwed in behind the last cartridge in the magazine, so as to retain the cartridges therein as a reserve when required, and allow the arm to be used as a single-firing gun.

In many instances it is important to increase the capacity of the magazine, especially in view of the rapidity with which this gun can be fired.

In Figs. 12 and 13 I have represented a magazine extension-tube C', the same having a socket to slip over the outside of the magazine-tube C, and there is a spring-clip, C⁵, or other fastening device to connect the magazine extension-tube to the magazine. This allows for the introduction of a large number of cartridges, and the spring c of the ordinary magazine and the follower c' pass into this magazine extension-tube, and to obtain the necessary range of motion an additional spring, c' , is provided within the magazine extension-tube C'. As a matter of convenience, this magazine extension tube may be pointed at the outer end and provided with a cross-piece, C', near the inner end to allow for its use as a weapon, if needed. A movable cap is to be provided for the end of the magazine-tube C when the extension-tube is removed, and I also find that it is important to keep moisture out of the barrel. In cases where corks or plugs have been made use of they are liable to be lost. I form the outer end of the barrel with a slightly-tapering bore of a size to receive a spent-cartridge case so that such a case can be used as a plug, and I find that it is much better than the plugs heretofore used because it is absolutely water-proof, and can be pulled out or replaced with great facility.

I find that it is preferable to make use of a steel plate at the end 26 of the sear S, because the same is exposed to both concussion and wear; but it is preferable to insert a plate of brass or copper between this steel plate and the end of the sear, in order that the comparatively soft metal may accommodate itself to the surfaces of the steel and act as a cushion in lessening concussion. Similar plates may be placed at the inner surfaces of the trigger-hook f' .

I claim as my invention—

1. The combination, with the tumbler K and the lock mechanism of the fire-arm operated by the tumbler and the spring, of a chain made of short links introduced between longer links, and the chain-wheels having pro-

jecting teeth that pass in between the pairs of longer links and acting against the shorter links, substantially as specified.

2. The combination, in a repeating fire-arm, 70 of a revolving tumbler, and the parts actuated by the same, chain-wheels and a chain, a helical expansive spring, a tube containing the same, a fusee-barrel, and a chain extending from the same to the follower of the helical 75 spring, substantially as set forth.

3. The combination, with the stationary lock-frame having the filling and ejecting chamber M, of the hinged door m, for said chamber, the axis 12 for the hinge of the door, 80 the crank-arm at the end of the same, and the spring 31 for closing said door, substantially as set forth.

4. The door m of the ejecting-chamber, hinged at the top and having a finger-piece, 85 m², with a mortise in the same, in combination with the spring-latch m³, and the side plate, E', that incloses the breech mechanism and to which the spring is attached, substantially as set forth.

5. The combination, with the revolving tumbler K, the trigger F', and trigger-sear S, of the arm n³ upon the end of the firing-pin sear, the sear end n⁶ below the arm n³, and the latch n⁸, both hinged to the sear-arm n³, the 95 shaft t', adjacent to the sear end, finger-piece t³, and blocking-piece t⁴ upon such shaft t', substantially as set forth.

6. The combination, with the trigger F' and its hook, revolving tumbler K, reciprocating breech-bolt, toggle-arms L³ and L⁴, and pin t¹, of the blocking-piece f⁶, extending out from the rear of the trigger-hook, with its end adjacent to the teeth 7 upon the tumbler K, substantially as and for the purposes set forth.

7. The combination, with the magazine below the barrel, the follower c' within the magazine, stop c² for the said follower, and finger-piece c³ outside the magazine, of the gravity-latch c⁴, connected to the stop, substantially as 110 and for the purposes set forth.

8. The combination, with the revolving carrier behind the barrel, and the magazine-tube below the barrel, of the follower c' within the magazine-tube, the stop below the follower, 115 the finger-piece outside the magazine for moving the stop and follower, and the screw c' passing in from outside the housing for clamping the follower, as and for the purposes set forth.

9. The combination, with the magazine-tube, of a removable extension magazine-tube adapted to set over the magazine-tube, and an additional spring within the same, and a fastening device for securing the extension-magazine in place, substantially as set forth.

Signed by me this 7th day of December A.D. 1885.

FRANK REES.
